PRESSURE-SENSITIVE ADHESIVE TAPE DISPENSER AND APPLIER

Walter C. Larsen, Minneapolis, Minn., assignor to Minnesota Mining & Manufacturing Company, St. Paul, Minn., a corporation of Delaware

Application April 27, 1954, Serial No. 30,217

Term of patent 14 years

(Cl. D74—1)

Figures 5 and 6 are front and rear elevational views, respectively.

I claim:

The ornamental design for a pressure-sensitive adhesive tape dispenser and applier, as shown.
